UNITED STATES PATENT OFFICE.

EDGAR J. CRAWFORD, OF SEATTLE, WASHINGTON, ASSIGNOR TO J. EUGENE JORDAN,
OF SEATTLE, WASHINGTON.

AUTOMATIC SPEED CONTROL.

1,398,539.

Specification of Letters Patent. Patented Nov. 29, 1921.

Application filed August 26, 1919. Serial No. 319,921.

To all whom it may concern:

Be it known that I, EDGAR J. CRAWFORD, a citizen of the United States, and resident of Seattle, Washington, have invented certain new and useful Improvements in Automatic Speed Controls, of which the following is a specification.

My invention relates to automatic speed control, particularly designed for use upon automobiles. The control, however, is applicable to all types of gas engines.

The object of my invention is to provide a speed control which may be set at certain pre-determined maximum speeds and which will shut off the engine automatically when it exceeds these speeds. Another object of my invention is to provide means for indicating maximum speeds for which the control is set, in connection with the regulating means.

My invention comprises the novel parts and combinations of parts which are herein described in the specification, defined by the claim terminating the same, and illustrated in the accompanying drawings.

In the accompanying drawings, I have shown my invention in the form which is now preferred by me:

Figure 1 is a section through the dash and hood of an automobile, illustrating my device mounted thereon, in side elevation.

Fig. 2 is a detail in section of a pair of contact members which I employ.

Fig. 3 is an elevation of the indicating device, parts being broken away.

In order to control the speed at which a gas engine may be run, I employ a governor, which is so mounted that it will cut off the electric current which includes the sparking system of the engine when the speed of the engine reaches a certain predetermined maximum. Such a device may be so regulated that the device may be set for certain maximum speeds, any one of which may be cut in or employed. Adjustments may also be made to set the device for any speed between two of the set maximum speeds.

The flexible shaft 1 which connects the speed indicator 10 with the wheel (not shown), has a bevel pinion 11 mounted upon a rigid portion 12 of the shaft. Preferably, this is mounted just inside the hood 2 of the car upon a frame 23 carried by the dash 20, and forms the last link of the flexible shaft 1.

A beveled pinion 31 meshes with the pinion 11 and rotates the governor shaft 32. The weighted arms 3 pivoted upon a collar 30 act upon a collar 33 and sleeve 34, which are slidably mounted upon the shaft 32 to press the sleeve upward against the resistance of a spring 36. Any other suitable form of governor, however, may be employed.

A flexible arm 4 mounted in any suitable way upon the frame 23 carries a plurality of contact points 40 and 41. The contact point or bar 42 is carried upon the frame 23, and is insulated therefrom. The flexible arm 4 is mounted in such a position as to be movable by the sleeve 34, acting under the influence of the governor 3.

The contact points 40 and 41 are connected to a selective switch 5 mounted upon the dash. This switch consists of an arm 50 secured upon a shaft 51 and movable by any suitable means from the driver's seat, as by the arm 52. The arm 50 forms one terminal of the battery circuit. The arm 50 contacts with a plurality of contact points 54 mounted upon the dash and each one connected to its respective contact point 40 and 41 upon the flexible arm 4 to complete the circuit. The contact point 42 is electrically connected to the battery 6 through the induction coil 61.

I prefer to mount the contact point 40 rigidly in the flexible arm 4, though adjustments may be made by means of nuts 44. The contact points 41 of which I have shown only one in the drawings are of a different type from the point 40. These consist of a contact member 41 secured upon the end of a conductor stem 43. The stem 43 extends upward through an opening in the insulator 45, which is fixedly secured in the arm 4, and slides in this insulator. A spring 46 tends normally to keep the point 41 in contact with the contact bar 42. Lock nuts 47 limit this projection of the point 41 beyond a certain pre-determined point. This may be regulated by adjustment of the lock nuts 47 upward or downward upon the stem. Though I have shown but one contact point of this type, it is evident that any number found necessary or desirable may be employed, in this way producing a finer regulation of the speed.

In operation this part of the device breaks the electric circuit which controls the spark 116

in the engine cylinder whenever the speed of the car (or in the case of a stationary engine, the engine speed) exceeds the controlling speed for which it has been set. If, 5 for instance, the speed limit within a certain district is twelve miles per hour, the contact point 40 is set so that the governor will not raise the arm 4 and the point 40 until this speed is reached by the car. The 10 contact point 40 is thrown into the circuit by connecting the arm 50 of the selective switch 5 with the contact point 54, which connects with the point 40. When the car reaches a speed of twelve miles per hour the 15 governor raises the arm 4, breaking contact between the points 40 and 42, and the engine fails to spark; thus its speed may not exceed twelve miles per hour.

If, in another district, the speed limit is 20 thirty miles per hour, the motorist, in passing from the twelve-mile district to the thirty-mile district, throws the switch 5 to the proper point 41 into circuit and the point 40 out. The point 41 will now be 25 held in contact with the bar 42 by means of the spring 46 until the lock nuts 47 contact with the insulator 45. This can be set to occur when the car speed reaches thirty 30 miles per hour. At this speed, then, the engine circuit is broken, and the speed is reduced. The device is capable of very exact 35 adjustment, and operates perfectly to limit the speed of the car to the maximum for which it is set.

35 In order to provide an indicator which will show the maximum speed at which the car may travel, I may employ a series of cards 7 having the controlling speeds written thereon, and arranged to move upward in a 40 box 71 to become visible, and downward out of sight. These cards 7 may be connected to an arm 72, secured upon the shaft 51, by means of links 73. The box 71, I prefer to 45 mount upon the hood of the car, facing forward, to serve as an indicator to traffic officers, pedestrians, and other motorists of the maximum speed at which the car may travel with the adjustment then made.

While I have described this invention 50 herein in connection with its application to an automobile, it is to be understood that this merely typifies the use to which it may be put in connection with any engine using an electric spark. The flexible shaft 1 is 55 herein described as connecting the speed indicator with the wheel, but it may be connected direct to the engine if desired, and in a stationary engine would be so connected. The electric circuit which is controlled 60 by this device may be the primary or secondary circuit of a gas engine, whichever may be found more suitable. Generally it would be connected in the primary.

It is to be understood that this speed control can be adapted to shut off the gas from

the carburetor automatically when it exceeds either of these pre-determined speeds.

I claim—

1. A speed control mechanism for gas engines comprising, in combination, an electric circuit adapted to produce a spark in the engine cylinders, a governor connected to the engine to be regulated by the speed thereof, a plurality of parallel circuit members, a selective switch adapted to throw any one of said parallel circuit members into the circuit and to exclude the remainder, an arm engageable by and movable by the governor, a fixed contact member, and a plurality of contact members carried by and movable with said arm out of contact with the fixed contact member, each of said movable contact members being connected with its respective one of said parallel circuit members, and each being movable out of contact with the fixed contact point at a pre-determined engine speed differing from the controlling speed of the other movable contact points. 75 80 85

2. A speed control mechanism for gas engines comprising, in combination, an electric circuit adapted to produce a spark in the engine cylinders, a governor connected to the engine to be regulated by the speed thereof, a plurality of parallel circuit members, a selective switch adapted to throw any one of said parallel circuit members into the circuit and to exclude the remainder, an arm engageable by and movable by the governor, a fixed contact member, and a plurality of contact members carried by and movable with said arm out of contact with the fixed contact member, each of said movable contact members being connected with its respective one of 90 95 100 105 said parallel circuit members, and each being movable out of contact with the fixed contact point at a predetermined engine speed differing from the controlling speed of the other movable contact points, an index 110 115 120 125 130

3. A speed control mechanism for gas engines comprising, in combination, an electric current including the sparking means in the engine cylinder, a governor connected to the engine to be regulated by the speed thereof, a sleeve axially movable upon the 120 125 130 governor shaft, a spring arm engageable by said sleeve and movable thereby at a pre-determined engine speed, a fixed contact point, a plurality of contact points fixed in said spring arm to move therewith, and normally contacting with the fixed contact point, said movable contact points being reciprocable in the spring arm in the direction of the fixed contact point, adjustable stops limiting the movement of these points

toward the fixed contact point, the movement of the arm breaking contact between said movable points and the fixed point at predetermined speeds, the speed varying for 5 each point, a plurality of parallel circuit members each connected to a movable contact point, and a selective switch adapted to throw any one of said parallel circuit members into the circuit and to exclude the remainder.

4. A speed control mechanism for gas engines comprising, in combination, an electric current including the sparking means in the engine cylinder, a governor connected to 10 the engine to be regulated by the speed thereof, a sleeve axially movable upon the governor shaft, a spring arm engageable by said sleeve and movable thereby at a predetermined engine speed, a fixed contact point, 15 a plurality of contact points fixed in said

spring arm to move therewith, and normally contacting with the fixed contact point, said movable contact points being reciprocable in the spring arm in the direction of the fixed contact point, adjustable stops limiting the 20 movement of the arm breaking contact between said movable points and the fixed point at predetermined speeds, the speed varying for each point, a plurality of parallel circuit members each connected to a movable contact point, and a selective switch adapted to throw any one of said parallel circuit members into the circuit and to exclude the remainder, an inclosing box, and a movable visible index of the controlling 25 speed movable into view from the box, and controllable by said selective switch.

Signed at Seattle, Washington, U. S. A., this 20th day of August, 1919.

EDGAR J. CRAWFORD.
